(57) **CLAIM**

The ornamental design for a lighted fish attractor, as shown and described.

DESCRIPTION

FIG. 1 is a front, left and top perspective view of the lighted fish attractor;

FIG. 2 is a front and top perspective view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown are included for the purpose of illustrating environmental structure and form no part of the claimed design.

The break lines are shown for convenience of illustration.
